UNITED STATES PATENT OFFICE

92,184

DESIGN FOR A RADIATOR CAP

Frederic A. Leisen, Grosse Pointe, Mich., assignor
to Stewart Die Casting Corporation, Chicago,
Ill., a corporation of Illinois

Application January 17, 1934, Serial No. 50,429

Term of patent 3½ years

To all whom it may concern:

Be it known that I, FREDERIC A. LEISEN, a citizen
of the United States, having residence at Grosse
Pointe, in the county of Wayne and State of
Michigan, have invented a new, original, and or-
namental Design for a Radiator Cap, of which
the following is a specification, reference being
had to the accompanying drawing forming a part
thereof.

In the drawing:

Figure 1 is a side elevation of a radiator cap
embodying my new design.

Figure 2 is a front elevation of the same.

Figure 3 is a top plan view.

I claim:

The ornamental design for a radiator cap sub-
stantially as shown.

FREDERIC A. LEISEN.
